UNITED STATES PATENT OFFICE

WILLIAM E. SHARP, OF CHICAGO, ILLINOIS

DESIGN FOR A COMBINED STAND AND RECEPTACLE FOR A CLEANING MACHINE OR THE LIKE

Application filed July 31, 1930. Serial No. 36,519. Term of patent 14 years.

To all whom it may concern:

Be it known that I, WILLIAM E. SHARP, a citizen of the United States, residing at Chicago, in the county of Cook and State of Illinois, have invented a new, original, and ornamental Design for a Combined Stand and Receptacle for a Cleaning Machine or the Like, of which the following is a specification, reference being had to the accompanying drawings, forming part thereof.

bined stand and receptacle for a cleaning machine showing my new design.

Figure 2 is a plan or top view of said cleaning machine.

I claim:

The ornamental design for a combined stand and receptacle for a cleaning machine or the like as shown.

In testimony whereof I hereunto affix my signature.

WILLIAM E. SHARP.
